RESERVOIR SPONGE

Pauline Mae Cullison, San Francisco, Calif.

Application November 17, 1950, Serial No. 13,037

Term of patent 14 years

(Cl. D9—2)

To all whom it may concern:

Be it known that I, Pauline Mae Cullison, a citizen of the United States of America, residing at 886 Sutter Street, San Francisco, in the county of San Francisco, State of California, have invented a new, original, and ornamental Design for a Reservoir Sponge, of which the following is a specification, reference being had to the accompanying drawing, forming a part thereof.

Fig. 1 is a perspective view of a reservoir sponge, showing my new design;

Fig. 2 is an end elevational view thereof;

Fig. 3 is a bottom view of the same;

Fig. 4 is a cross-sectional view of the handle taken on the line 4—4 of Fig. 1.

I claim:

The ornamental design for a reservoir sponge, as shown.

PAULINE MAE CULLISON.
